CASH REGISTER

Ernst Breitling, Berlin-Tempelhof, Germany, assignor to The National Cash Register Company, Dayton, Ohio, a corporation of Maryland

Application April 21, 1939, Serial No. 269,297
In Germany April 27, 1938

2 Claims. (Cl. 235—8)

This invention relates to improvements in differential mechanisms of the type used in cash registers and accounting machines, and particularly to differential mechanisms employed for setting up data to be recorded during adding operations and for printing the highest order digits of a total during total-taking operations.

The object of the invention is to provide a differential mechanism of the type in which two actuators are provided, one of which is provided to set up data during adding operations and the other of which is provided to set up the highest order digits of a total during total-taking operations, with a novel latch mechanism.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

Of said drawings:

Fig. 1 is a sectional side view of the differential mechanism.

Figs. 2 and 3 are details of the mechanism shown in Fig. 1.

Fig. 4 shows the machine releasing mechanism and a portion of the controls therefor.

Fig. 5 is a detail of a part of the total taking control means.

Fig. 6 shows the motor or machine release bar and part of the machine release means.

Fig. 7 is a sectional view of a part of the total taking control means and a part of the machine release means.

Fig. 8 shows part of an amount bank and the means for preventing operation of amount keys during total taking.

Special differentials

The differential mechanism comprising the present machine has been applied to a machine wherein one or more banks of keys are used for setting up data. These banks of keys are conveniently arranged to the left of the amount entering keys, such as the amount key 201 shown in Fig. 1 of the United States patent to Ernst Breitling, No. 2,052,444, issued August 25, 1936.

The special differential disclosed herein is used during add operations of the machine for data which are not entered into a totalizer. Since the differentials are located to the left of the amount entering banks of keys, they may be located opposite overflow wheels of the totalizer, and controls

are provided whereby the differentials can be utilized for setting up amounts standing on the overflow wheels of the totalizer. By this arrangement, the size of the keyboard need not be increased nor the totalizer capacity reduced. A similar arrangement is shown and described in the United States patent to Robertson, No. 1,929,652.

The differential (Fig. 1), facing the two right-hand totalizer orders and cooperating with quantity keys 11 in amount entering, must not transmit their setting to adding wheels 21 of these two right-hand totalizer orders, but must zeroize the adding wheels of these orders in total taking. To obtain this result, the differentials of these orders are provided with a main differential member 41a and an auxiliary differential member 41b (Figs. 1, 2 and 3). On a pin 42 of the auxiliary member 41b a pawl 43 is mounted. Said pawl 43 has a pin 45 which, by the action of a spring 44 tensioned between the pawl 43 and the auxiliary member 41b, bears against a lug of a lever 46 pivoted on a stud 47, which also supports a zero stop pawl 48 of said key bank. The lever 46 engages a pin 49 of a lever 50 mounted on a shaft 200. The shaft 200 is retained in its initial position during all adding operations, but is rocked counter-clockwise to and fro by the machine drive in all total taking operations by means hereinafter described. As long as the machine is set to adding, the lever 50 and the lever 46 remain in the positions shown in Fig. 1, whereby a clockwise rotation of the pawl 43 due to the action of the spring 44 is prevented.

The special differentials (Fig. 3) also include the coupling pawl 82, setting member 83, and actuator 80, the latter being connected by a link 86 to the arm 87 (Fig. 1) mounted on the rod 88 and guided by the block 89 on the shaft 90. The spring 112 (see also Figs. 2 and 3) connects the main member 41a and the setting member 83, and the pawl 82 and its pin 106 couple the actuator 80 to the member 41a. The cams 95 and 96, through the levers 91 and arms 87, operate the rod 88 and link 86 to drive the actuator 80 first clockwise and then counterclockwise to their original positions. The actuator 80, through the stud 111, restores the parts 41a, 41b, and 83 to their normal positions at the proper time.

Upon depressing a quantity key 11, a detent 51 allotted thereto is shifted upwardly and a pin 52 on said detent 51 rocks the zero stop pawl 48 and moves its pin 53 out of the path of the setting member 41a. Now, upon actuation of the machine, the differential member 41a is

rocked by its actuator 80 until said member is arrested by the stem of the quantity key depressed, and the associated type wheel is set accordingly in a manner described below. The auxiliary differential member 41b remains in its initial position, as it is not coupled with the member 41a, as the lug of the lever 46 is located in front of the pin 45 of the pawl 43 and prevents any undesired movement of the auxiliary member 41b. Consequently the quantities set up by the quantity keys 11 depressed, are not entered into the totalizers.

Totalizer

The totalizer illustrated herein is a totalizer of the general type illustrated in the above-named Breitling patent. Only the overflow wheels of such a totalizer are illustrated herein.

The overflow wheels 21 (Fig. 1), mounted on shaft 23, control the differential setting of the differential mechanism during total-taking operations.

During adding operations, when the highest order totalizer wheel passes from 9 to 0, the tens transfer mechanism adds one into the first overflow wheel 21. When the first overflow wheel passes from 9 to 0, due to repeated tens transfers therein, a tens transfer disk 24, connected to the overflow totalizer wheel 21, trips a tens transfer mechanism (not shown) to cause "1" to be entered into the next higher order overflow wheel, through the medium of a transfer segment 31.

The overflow wheels 21 are connected with the differential mechanism through gears 22 and 35, the totalizer wheels 21 being rocked into engagement with gear 22 at the proper time by mechanism not shown herein. The gear 35 (see also Fig. 2) is always in mesh with the auxiliary member 41b, the former being mounted on a nest of sleeves on shaft 40.

Certain elements of the tens transfer mechanism, such as shafts 26 and 28, stud 32, arm 33, and disk 38, are shown herein, but not described, since an understanding of the exact form of transfer mechanism shown herein is not necessary to a clear understanding of the present invention, since any form of transfer mechanism will operate equally successfully with the present invention.

Total taking

For total taking, the shaft 200 is rocked counter-clockwise (Figs. 1 and 5) through a certain angle, as will be hereinafter described, in connection with the machine releasing means. The two levers 50, one for each bank of quantity keys, are secured to the shaft 200 and rotate their associated levers 46 clockwise and release the pawls 43 to follow under action of their springs 44. Also, by means of pins 54 on the zero stop pawls 48, the latter are rotated clockwise, whereby the pins 53 of the zero stop pawls are moved out of the paths of the differential member 41a. The springs 44 rock the pawls 43 so far that their lower working surfaces bear on a lug 55 secured to each of the members 41a, thus connecting the members 41a and 41b. Upon operation of the machine, the driven differential member 41a carries along the auxiliary differential member 41b coupled therewith, which rotates the engaged adding wheel 21 counter-clockwise until a projection of the tens transfer disc 24 engages a tooth of the tens carrying pinion 31 and stops it in its zero position. Thus,

the differential members 41b and 41a are stopped in a position corresponding to the amount taken from the respective adding wheel, and such amount is transmitted to the type wheel in a manner to be specified immediately.

During the return movement of the differential member 41a, the auxiliary differential member 41b associated therewith is positively returned into its initial position by a pin 56 of the auxiliary member 41b being engaged by the member 41a. Upon the return of the shaft 200, the members 41a and 41b are disengaged and all the parts are again in their initial positions according to Fig. 1.

Machine releasing means

The machine releasing mechanism will be described only in connection with total taking operations. For a full description of all releasing means and controls therefor, reference may be had to the Breitling, Topel, and Philipp application, Serial No. 238,546, filed November 3, 1938.

Connected to the motor bar 19 (Fig. 6) is a plate 121 having a pin 123 cooperating with a lever 124 pivoted on a stationary stud 125 and connected by a link 126 to an arm 127 mounted on a shaft 122. The arm 127 is connected to a bail 128 (Fig. 4) loose on the shaft 122 but connected to a tube 129. The bail 128 is connected to an arm 132 loose on a shaft 120, by a link 131. A spring 133 (Fig. 6) tends to keep the motor bar 19 in its normal position.

A stud 135 (Fig. 4) of a slide 136 bears against the lever 132. This slide 136 is pivoted to a lever 137 and is guided on a rod 138. The lever 137 is pivoted on a stud 140 of a slide 141 of the transaction bank of keys 15 and is held in its upper position by a spring 142.

Joined to the lever 137 is a link 144 connected to an arm 145. A lever 146 is adapted to be moved into the position shown in Fig. 4 by the depression of any of the keys 14 to 17 to arrest or prevent movement of the arm 145 upon depression of the motor bar 19, so that the machine will be released during total taking operations when one of the control keys 14 to 17 is operated.

Depression of the motor bar 19 rocks the lever 132 counter-clockwise and, as the arm 137 cannot rock on its pivot stud 140, due to the arm 146 being in the path of arm 145, said arm 137 pivots on the link 144 and the stud 140 carries the slide 141 against the action of the spring 142.

A pin 161 of the slide 141 is embraced by a forked lever 162 pivoted on a stationary stud 165. The lever 162 is secured to a pawl 163, a hook 164 of which normally lies beneath a lug 166 of a slide 167 of the bank of keys 15. A spring 168 tends to pull the slide 167 down, but is prevented from doing so by the hook 164.

However, when the slide 141 is lowered, as above described, upon operation of the control keys, the pin 161 rocks the pawl 163 and releases the slide 167 to the action of the spring 168.

A link 171 (Figs. 4 and 7) connects the slide 167 to an arm 172 secured to a tube 173 connected to a release bail 170 loose on the shaft 200. An arm 174 of the bail 170 carries a stud for a block 175 pivoted thereon. The block 175 slides in a slot of a lever 176 pivoted on a stationary stud 177. A spring 178 tends to rock the lever 176 clockwise, thus tending to aid the spring 168.

An arm 180 (Figs. 4 and 7) of a two-armed lever is loose on the shaft 200 and bears on an arm 179 of the lever 176. Another arm 181 of

said two-armed lever faces a node 169 of said lever 176.

A link 183 is pivoted on a stud 160 of the arm 180 and connects said arm 180 to a machine locking lever 184 pivoted on a stationary stud 185.

Normally, one arm of the lever lies under a plate 188 secured to a gear 187 fast on the drive shaft 92. A roller 189 attached to the gear 187 cooperates with an arm 186 of the lever 184, and a spring-drawn arm 191 bears on said arm 186.

When the motor bar 19 (Fig. 6) is depressed and the slide 167 (Fig. 4) is pulled down by the spring 168 when a control key 15 is depressed as above described, the spring 168, aided by the spring 178, rocks the bail 170 and lever 176 clockwise. Thus the arm 179 releases the arm 180 to the action of the spring 182, whereupon the lever 184 is withdrawn from the plate 188 and the arm 191 rides off the arm 186 to close a motor circuit, and the shaft 92 is then given one counter-clockwise rotation.

Secured to the shaft 200 (Figs. 4, 5, and 7) is an arm 198 held against the stud 160 by a spring 199. In addition to the above-mentioned levers 50 for the quantity banks, there is also secured to the shaft 200 a lever 195 (Figs. 7 and 8) for each amount bank of keys 10. Each lever 195 cooperates with a pin 194 of its associated zero stop pawl 103 to rock the latter and remove its pin 105 away from the differential members 41 during total taking operations.

Therefore, when the stud 160 (Figs. 4, 5, and 7) is raised upon release of the machine, as above described, the spring 199 rocks the shaft 200 counter-clockwise (Figs. 4 and 5) and clockwise as viewed in Fig. 8, whereupon the levers 195 rock the amount zero stop pawls 103 to release the differential members 41 associated with the amount banks of keys 10, and the levers 50 (Fig. 1) rock the quantity zero stop pawls 48 to release the differential members 41a so that all differentials can be controlled by their associated adding wheels 21 to adjust any desired recording medium to amounts representing the totals taken from said wheels.

During adding operations, the shaft 200 cannot be rocked by the spring 199, even though the stud 160 is raised upon release of the machine, as depression of any amount key 10 (Fig. 8) moves a flange 197 in front of a hook 196 on the lever 195, and moreover, depression of any key 11 moves a flange 193 (Fig. 1) of its respective detent 51 in front of a hook 192 of its associated lever 50.

During total taking operations, said hooks 196 and 192 are moved over the tops of their respective flanges 197 and 193 when the shaft 200 is rocked as above described, thus preventing operation of any of the keys 10 or 11 during total taking operations.

At the end of the operation, the roller 189 (Fig. 4) restores the lever 184 to normal position, whereupon the link 183 restores the arm 180 and the stud 160 restores the arm 198, shaft 200, and levers 195 and 50 to their normal positions.

While the form of mechanism herein shown and described is admirably adapted to fulfill the objects primarily stated, it is to be understood

that it is not intended to confine the invention to the one form or embodiment herein disclosed, for it is susceptible of embodiment in various forms, all coming within the scope of the claims which follow.

What is claimed is:

1. In a differential mechanism of the class described, the combination of a driving member; two driven members, one of said driven members being differentially settable from a normal home position into a differentially set position by said driving member at each operation thereof; a projection on said one driven member; a pawl pivoted on the other one of said driven members; a working surface on one end of the pawl; a resilient means normally urging the pawl into a position wherein the working surface of the pawl coacts with the projection on said one driven member, said pawl being pivoted on said one driven member in such a position that the working surface of the pawl always tends to move in a direction away from a point about which said driven members pivot; an element normally engaging the pawl to restrain the pawl in a position wherein the working surface thereof is disengaged from the projection on said one driven member; a control means coacting with the element to withdraw the element from engagement with the pawl to release the pawl to the action of the resilient means whereby the resilient means moves the working surface of the pawl into the path of the projection on said one driven member, whereby the differential movement of said one driven member can be transmitted to said other driven member when the said one driven member is moved out of its home position; and means on said other driven member engageable by the said one driven member to restore the said other driven member to its home position when said one driven member is moved back to its home position.

2. In a differential mechanism of the class described, the combination of a driving member; two driven members, one of said driven members being differentially actuated from home position to a differentially set position by the driving member at each operation thereof; a clutch member pivotally mounted on the other one of said driven members and intermediate the two driven members whereby the differential actuation of said one driven member may be transmitted to said other one of said driven members, said clutch member being normally in an ineffective position; resilient means normally urging said clutch member toward effective position; means normally engaging said clutch member to hold the clutch member in ineffective position; control means for withdrawing said clutch member holding means to permit said resilient means to move said clutch member to effective clutching position, the clutch member being pivoted to move away from the center of movement of the two driven members when moved into effective position by the resilient means; and means on said second driven member coacting with the first driven member to connect the driven members for unitary movement in a direction back to home position.
